233,218

PACKAGING CONTAINER OR THE LIKE

Elmer C. Lynn, 405 Kimberly Lane,
Des Moines, Iowa 50317

Filed Sept. 29, 1972, Ser. No. 293,483

Term of patent 14 years

Int. Cl. D9—03

U.S. Cl. D9—219

FIG. 1 is a perspective view of a packaging container or the like showing my new design;

FIG. 2 is a top plan view;

FIG. 3 is a side elevational view, the opposite side being the same in appearance as the side shown;

FIG. 4 is an elevational view looking from the right of FIG. 3, the opposite side being the same in appearance as the side shown; and

FIG. 5 is a bottom plan view thereof.

I claim:

The ornamental design for a packaging container or the like, substantially as shown and described.

References Cited

UNITED STATES PATENTS

D. 212,831	11/1968	Koch	-----	D7—187
2,780,386	2/1957	Evans.
3,166,234	1/1965	Amberg.

ROBERT C. SPANGLER, Primary Examiner